UNITED STATES PATENT OFFICE.

EDWARD BELLAVANCE, JR., OF MOOSUP, CONNECTICUT.

MACHINE FOR STRAIGHTENING LOOM-SHUTTLES.

1,161,828.

Specification of Letters Patent. Patented Nov. 30, 1915.

Application filed July 28, 1915. Serial No. 42,362.

To all whom it may concern:

Be it known that I, EDWARD BELLAVANCE, Jr., citizen of the United States, residing at Moosup, in the county of Windham and State of Connecticut, have invented or discovered certain new and useful Improvements in Machines for Straightening Loom-Shuttles, of which the following is a specification, reference being had therein to the accompanying drawings.

This invention relates to a machine for straightening up the sides of loom shuttles when they have become worn or rounded in use.

To this end the invention comprises a holder for the shuttle which is adapted to be reciprocated in proximity to a rotary grinding disk, as will hereinafter more fully appear.

In the accompanying drawings Figure 1 is an end view, with parts broken away in vertical section, of the improved machine, and Fig. 2 is a plan view of the same.

Referring to the drawings, *a* denotes a framework or table mounted on suitable standards or legs *b*. Attached to the framework or table *a* is a bracket *a'* affording bearings for a driving shaft *i* to the inner end of which is attached a grinding disk *c* rotating in an opening in the said framework or table *a*, the working face of said disk being covered with sand paper or other abrasive material glued or otherwise suitably attached thereto.

The shaft *i* is provided with a loose pulley *p*, a fast or driving pulley *o* and a grooved pulley *l*. Said shaft *i* is slidingly mounted in its bearings in the bracket *a'* so that it may be adjusted endwise through the pulleys *l*, *o* and *p*, but the said pulleys *l* and *o* are connected thereto, so as to rotate therewith, by means of a spline *i'*. Extending upward from the framework or table *a* is a standard *a²* from which extends laterally a rod *h* supporting a belt guide *h'* which is slidingly mounted on said rod so that it may be adjusted by means of a handle *h²* to shift a driving belt from the fast pulley *o* to the loose pulley *p*, or vice versa.

Mounted to reciprocate on the framework or table *a* is a slide *d* which may be guided in any suitable manner on said framework, or table, as by being provided on its under side with ribs or projections *t'* entering slots *d'* in the said framework or table. Attached to the slide *d*, by set screws *g*, are shuttle hold-

ing blocks *e* having V-shaped recesses for receiving the pointed ends of a shuttle, the said blocks *e* being overlaid by plates *f* beneath the heads *g'* of the screws *g* so that the said plates, in connection with said blocks *e*, will serve to hold a shuttle securely to the slide *d* with the side of such shuttle in contact with the grinding disk *c*. The slide *d* and the shuttle-holding parts, just described, mounted thereon, constitute a shuttle holder or carrier to coöperate with the grinding or abrasive disk *c*.

The disk *c* may be adjusted to bring it into suitable working contact with a shuttle held on the shuttle-carrying slide *d* by means of an adjusting screw *q* tapped in the bracket *a'* and having a swiveled connection with a bar *n* attached to one end of the shaft *i* by a screw *n'*, the shaft being maintained in any desired position of adjustment by means of a set screw *s* one end of which abuts against the bracket *a'*.

The pulley *l* is connected by a belt *m* with a large pulley *k* on a shaft *j* suitably journaled in a support on the framework of the machine and provided at its inner end with a disk carrying a crank *u* joined by a connecting rod *t* with one of the projections *t'* extending downward from the slide *d*, so that by the rotation of the said shaft *j* the said slide will be reciprocated back and forth relative to the framework or table *a*.

From the foregoing it will be understood that when a shuttle to be straightened is mounted on the reciprocating slide *d* and the machine is set in operation, the coöperative action of the said reciprocating slide *d* and the grinding disk *c* will serve to grind away and straighten the side of said shuttle which will be contiguous to said disk; and when one side of the shuttle has been straightened the said shuttle may be reversed in its holder and the other side thereof be operated on to grind and straighten the same. In this operation of the machine the shaft *i* may be adjusted endwise by means of the screw *q*, as circumstances may require, to bring the grinding disk *c* into proper relation to the shuttle being straightened.

The invention is not to be understood as being limited to the details herein shown and described, as these may be varied widely, within the limits of mechanical skill, without departing from the scope of the invention.

Having thus described my invention I claim and desire to secure by Letters Patent:

1. In a machine for straightening loom shuttles, the combination with a shuttle holder or carrier comprising blocks having V-shaped recesses adapted to receive the pointed ends of a shuttle, of a grinding disk disposed adjacent to said shuttle holder or carrier, an endwise adjustable rotary shaft by which said disk is carried, and means for reciprocating the said shuttle holder or carrier relative to said rotary grinding disk. 50
2. In a machine for straightening loom shuttles, the combination with a shuttle holder or carrier comprising blocks having V-shaped recesses adapted to receive the pointed ends of a shuttle, of a grinding disk disposed adjacent to said shuttle holder or carrier, an endwise adjustable rotary shaft 55 by which said disk is carried, and means for reciprocating the said shuttle holder or carrier relative to said rotary grinding disk. 60
3. In a machine for straightening loom shuttles, the combination with a shuttle holder or carrier comprising blocks having V-shaped recesses adapted to receive the 65 pointed ends of a shuttle, of a grinding disk disposed adjacent to said shuttle holder or carrier, an endwise adjustable rotary shaft by which said disk is carried, driving and belt pulleys having a splined connection with 70 said shaft, and means for reciprocating the said shuttle holder or carrier relative to said rotary grinding disk. 75
4. In a machine for straightening loom shuttles, the combination with a shuttle holder or carrier, comprising blocks having V-shaped recesses adapted to receive the pointed ends of a shuttle, of a grinding disk disposed adjacent to said shuttle holder or carrier, an endwise adjustable rotary shaft 80 by which said disk is carried, driving and 85 the said shuttle holder or carrier relative to said rotary grinding disk.

belt pulleys having a splined connection with said shaft, and means for reciprocating the said shuttle holder or carrier relative to said rotary grinding disk, said means comprising a crank and driven from said first-named shaft.

5. In a machine for straightening loom shuttles, the combination with a suitable framework or table, of a shuttle carrier or holder mounted to reciprocate on said framework or table and comprising recessed blocks adapted to receive the pointed ends of a shuttle, a grinding disk disposed adjacent said shuttle carrier or holder, an endwise adjustable rotary shaft by which said disk is carried, pulleys on said shaft, an adjusting screw by which said shaft may be moved endwise, and a set screw for fixing said shaft in any desired position of adjustment. 60

6. In a machine for straightening loom shuttles, the combination with a shuttle holder or carrier comprising recessed blocks adapted to receive the pointed ends of a shuttle, of a grinding disk disposed adjacent to said shuttle holder or carrier, an endwise adjustable rotary shaft by which said disk is carried, and means for reciprocating the said shuttle holder or carrier relative to said rotary grinding disk. 70

7. In a machine for straightening loom shuttles, the combination with a shuttle holder or carrier comprising recessed blocks adapted to receive the pointed ends of a shuttle, and plates overlying said blocks and adapted to hold a shuttle to the body of said carrier, of a grinding disk disposed adjacent to said shuttle holder or carrier, an endwise adjustable rotary shaft by which said disk is carried, and means for reciprocating the said shuttle holder or carrier relative to said rotary grinding disk. 80

In testimony whereof I affix my signature.

EDWARD BELLAVANCE, JR.
